CHURN ATTACHMENT

Guy T. Kilmer, Middle Grove, N. Y.

Application August 6, 1941, Serial No. 405,663

3 Claims. (Cl. 259—1)

This invention relates to a churn and a device for attaching the churn to a washing machine.

The churning of butter is frequently done at the dwelling house, usually by continuous rotation of the churn in one direction with paddles in the container for the cream to provide the desired agitating action. Many dwellings at the present time have electric power and electric machinery for utilizing the electric energy supplied. Among such machinery, a washing machine is frequently used, to which attachments may be applied for accomplishing other objects than the washing of clothes. The washing machine agitator has an oscillatory motion through substantially 180 degrees in one direction and then back through 180 degrees in the other direction. The utilization of this oscillatory motion for the churning of butter instead of continuous rotation in one direction presents several difficulties, especially with a circular container for the cream equipped with paddles, and the movement of the container on the agitating vanes of the washing machine. Also, in the use of a churn with paddles it is difficult to clean the equipment.

One of the objects of this invention is to provide a simple and inexpensive churn which may be mechanically operated by attachment to a washing machine.

Another object of the invention is to eliminate the necessity of the use of paddles in the cream container for churning butter.

Another object of the invention is to provide a container which will be so shaped that the paddles within the container are unnecessary.

Another object of the invention is to provide a cream container which may be easily cleaned such for instance as by the provision of a smooth interior surface.

Another object of the invention is to provide a mounting for the cream container which may serve to attach it to the agitator of many different makes of washing machines now on the market.

Another object of the invention is to provide for the simple and easy positioning and removal of the churn on the vanes of the washing machine so that it may be retained in position by its own weight.

With these and other objects in view, the invention consists of certain novel features of construction, as will be more fully described and particularly pointed out in the appended claims.

In the accompanying drawings:

Fig. 1 is a sectional view illustrating a portion

of the washing machine including the agitator, together with the churn and its mounting upon the agitator;

Fig. 2 is a sectional view on line 2—2 of Fig. 1 of the cream container;

Fig. 3 is a sectional view on line 3—3 of Fig. 1;

Fig. 4 is a sectional view on line 4—4 of Fig. 1 of a fragmental portion;

Fig. 5 is a sectional view of the cream container alone;

Fig. 6 is a sectional view of the mounting frame;

Fig. 7 is a top plan view of the mounting frame;

Fig. 8 is a perspective view of the churn or cream container.

In proceeding with this invention, I provide some out-of-round container so that its oscillatory movement will disturb the contents within rather than merely slipping about the liquid contents with a minimum agitation; and I thus utilize the oscillatory motion given to the liquid container. By shaping this container substantially in the pattern of an oval, the disturbance provided is of such extent that no paddles in the cream are required for agitation. The oval also permits of easy cleaning, and thus a very simplified form of device is present by this shaping of the churn. This shaping also permits of a

simplified mounting, it being unnecessary to provide paddles for movement with reference to the container. Thus, I may provide a framework with a plurality of adjustable legs, usually three in number, which may be moved to a position to engage the agitator of a washing machine so

that it may be set thereon and be held by its own weight; and thus the oscillatory motion of the agitator of the washing machine will be imparted to the framework and through the framework to the churn for the agitating of the cream therein; and the following is a more detailed description of the present embodiment of this invention, illustrating the preferred means by which these advantageous results may be accomplished.

With reference to the drawings, 10 designates the outer casing of a washing machine having a bowl portion 11 through the bottom of which there extends shaft 12 which carries a bell-like agitator 13, hollow as at 15 and having a plurality of vanes extending therefrom. The vanes comprise three large vanes 14 and three small vanes 16, as shown in Fig. 3, and extend radially from the axial center of the shaft 12. These vanes are curved inwardly and upwardly from the

periphery of the bell and merge into a hub 16 which is standard equipment of one type of washing machine, while other makes have similar or different agitators with vanes for performing the function of washing clothes and to which my invention is adaptable.

The churn or cream container is designated generally 20 and is shown in perspective in Fig. 8, while it is shown in section in Figs. 1, 2, and 5. The general form of this container is tubular having a side wall 21 with a smooth inner surface 22. The tube, however, is not of uniform shape throughout its length, but rather is elliptical at its lower portion 23 and cylindrical at its upper portion 24, one shape merging into the other as may best be seen in Figs. 2 and 8. An elliptical bottom wall 25 is provided with a down-turned flange 26 which is soldered as at 27 to the side wall 21. Suitable openings 28 are provided through the flange 26 and lower edge of the bottom wall providing a reinforced portion for mounting of the churn, as later will be more fully described.

A cover 29 having a handle 30 and flange 31 may telescope into the top of the churn and be lifted therefrom for access to the contents of the churn. The usual pouring spout (not shown) will be provided in the cover. Handles 32 are provided at diametrically opposite points near the top of the churn for lifting or carrying the churn from one place to another.

The oval arrangement of the bottom portion of the churn when oscillated causes a violent agitation or excitement of the liquid contents of the churn which is sufficient to perform the butter-making action without the use of a paddle.

In order to mount this container or churn 20 on the agitator 13, I have provided a framework designated generally 35 and shown alone in Figs. 6 and 7. This framework is designed primarily for the convenient mounting of legs for attachment to the churn and the supporting of the churn on the agitator. One convenient formation of the frame is by means of a plate 36 with a down-turned flange 37, forming an upper portion of the frame. This plate will be of a size and shape to fit the recess 38 of the bottom portion of the churn and is a convenient mounting for brackets 39 on which the legs 40 are hinged. The lower portion of the frame consists of an annular member 41 which provides for holding the legs in the desired position of adjustment. This annular member 41 is attached to the upper plate 36 by struts 42 secured at intervals, and here shown as three in number, for spacing these two parts 36 and 41, as seen in Fig. 6.

The legs which form the primary holding and supporting function are positioned in this framework to have considerable freedom of movement, and each consists of a channel or U-shape in cross section, perhaps best seen as to their cross-sectional shape in Fig. 3. Each leg is pivotally mounted in a bracket 39 by means of a bolt 43 and nut 44 (see Fig. 4) and is adapted to swing about the bolt 43 as a hinge axis. These legs are three in number and by reason of the location of the brackets are positioned equally angularly about the axial center of the frame. The lower portions 45 of these legs will engage between the vanes 14 and 46 and will be held from

outward movement by reason of the links 47 which are clamped in adjusted position, as shown in Fig. 1, to the annular member 41 by bolts 48 and wing nuts 49 which extend through an opening in the annulus 41 and through one selected opening 50 in the link 47. Thus, these legs may be swung inwardly or outwardly about their hinge 43 to provide different spacings in the center and provide sufficient adjustment so that many different agitators may be accommodated.

The frame is secured to the lower part of the churn by openings 51 in the flange 37 registering with openings 28 for the reception of bolts 52 (see Fig. 1) and wing-securing nuts 53, whereby the framework is secured to the churn and becomes an assembled unit therewith. This assembled unit of churn and mounting frame may be lifted from the agitator of the washing machine and may rest upon any flat horizontal surface by reason of the annulus 41 being in substantially a single plane below the legs. Thus, this annulus serves as a rest for the churn when out of working position as well as a holder for the supporting legs when in working position.

I claim:

1. In a mechanically operated churn, a frame for mounting the cream container on a washing machine agitator comprising an upper member and a lower member, means for securing said members together in spaced relation, the lower member being provided with an opening adapted to axially receive a washing machine agitator, a plurality of legs for engaging the agitator, at least one of the legs having a portion extending axially of the frame and hinged to the upper member and a portion extending radially of the frame and movable in adjacency to the lower member and means to secure said movable leg to the lower member in selected adjusted position.

2. In a mechanically operated churn, a frame for mounting the cream container on a washing machine agitator comprising an upper member and a lower member, means for securing said members together in spaced relation, the lower member being provided with an opening adapted to axially receive a washing machine agitator, a plurality of legs for engaging the agitator, each of the legs having a portion extending axially of the frame and hinged to the upper member and a portion extending radially of the frame and movable in adjacency to the lower member, and means to secure said legs to the lower member in selected adjusted position.

3. In a mechanically operated churn, a frame for mounting the cream container on a washing machine agitator comprising an upper member and a lower member, means for securing said members together in spaced relation, the lower member being provided with an opening adapted to axially receive a washing machine agitator, three legs for engaging the agitator, each of the legs having a portion extending axially of the frame and hinged to the upper member and a portion extending radially of the frame and movable in adjacency to the lower member, and means to secure said legs to the lower member in selected adjusted position.

GUY T. KILMER.
